UNITED STATES PATENT OFFICE.

WILLIAM R. KEENEY, OF DOON, IOWA, ASSIGNOR OF ONE-HALF TO SAMUEL J. BEALS, OF SIOUX CITY, IOWA.

AUTOMATIC BLOCK FOR RAILROAD-SWITCHES.

SPECIFICATION forming part of Letters Patent No. 642,232, dated January 30, 1900.

Application filed April 24, 1899. Serial No. 714,287. (No model.)

To all whom it may concern:

Be it known that I, WILLIAM R. KEENEY, a citizen of the United States, residing at Doon, in the county of Lyon, State of Iowa, have invented a new and useful Automatic Block for Railroad-Switches, of which the following is a specification.

My invention relates to a safety device or block for railroad-switches; and the objects 10 of the invention are, first, to so occupy, fill, and divide the space between the movable and the main or stock rail of the form of switch known as a "split switch" as to avoid the dangers common and incident to such switches 15 occasioned by the catching of the feet of the employees or others in such space; second, to supply a block for such switch of such form and so adjusted that it will not interfere with the movement and operation of the 20 switch, but will move automatically with the switch-point in such a way as to block or divide the space when open; third, to supply a form of said block that may be readily and easily adjusted to existing construction, and, 25 fourth, to supply a block so constructed that it may be rapidly and easily removed and replaced for the purpose of removing snow, ice, or other obstructions. I attain these objects by the mechanism illustrated in the accompanying drawings, in which—

Figure 1 is a view of a split switch open with the device in place. Fig. 2 shows a form of hinge by means of which the bar *a a* may move laterally at the free end. Fig. 3 shows 35 an end view of the switch open. Fig. 4 shows the switch shut. Fig. 5 is another view of the hinge shown in Fig. 2. Fig. 6 shows an end view of the switch closed.

In Figs. 1 and 4, *A* is the movable or split 40 rail of the switch, *B* the main or stock rail, and *a a* a bar or strip of metal, wood, or other material one-half inch to one inch in thickness, two to three inches in width, and about the length of the movable rail, although these 45 dimensions are not material. The bar or strip *a a* is shown attached to the movable or split rail by the hinge *b c*, which is bolted to the rail; but it may be attached to the main rail if for any reason such attachment is more 50 convenient. The method of attachment to the rail is also immaterial. The hinge as

shown may be used or a hook or other method of attachment, or the bar or strip may be attached directly to the rail, depending upon the flexibility of the bar or strip to permit the 55 movement of the free end.

The end *F* of the bar or strip at the point of the switch-rail, as shown in Fig. 3, is held in its position when the switch is open by the bracket *E*, attached to the sliding bar *G H*. 60 This sliding bar running under the main or stock rail and resting and sliding upon the head-block of the switch is turned up into a hook at *H*, which catches upon the base of the main rail *B* when the switch is open and 65 prevents further movement of the bar or strip toward the split rail, while in like manner a hook *D*, (shown in Fig. 1,) attached to the bar or strip, catches upon the end of the split rail *A* and prevents movement toward the 70 main rail *B*.

In the operation of the automatic block the bar or strip *a a* is attached by the hinge *b c* or otherwise at one extremity to the rail *A* or *B* in such manner that the bar or strip divides the space between *A* and *B* into about 75 equal portions at the opposite extremity of the bar or strip, which should reach to or slightly beyond the end or point of the split rail. The sliding bar *G H* is placed under the 80 main or stock rail and rests and slides upon the head-block of the switch, as indicated in Figs. 3 and 6, so that when the switch is open the hook *H* will catch upon the base of the rail *B* and the hook *D* upon the end of the rail *A*, 85 and the bar or strip will thus be held and supported in place about midway of the space between the rails. When the switch is closed, the split rail will be pushed against the bar or strip *a a*, which, moving toward the main 90 or stock rail *B*, will pass beneath the head of the rail *B*, occupying the position shown by the dotted line in Fig. 4 and by *F* in Fig. 6, thus permitting the split rail *A* to close against the rail *B*. When the switch is again thrown 95 open, the rail *A*, catching the hook *D*, pulls the bar or strip again into position, as shown in Figs. 1 and 3. The space between *A* to *B* being thus divided by the bar *a a*, it is impossible for a person to put his foot into the 100 space or get it caught there. The strip or bar can be readily detached for the purpose

of removing snow or ice by lifting it from the hinge or hook at the attached end.

So far as I am aware prior to my invention there has been no device calculated to accomplish the objects of this automatic switch-block by a horizontal movable bar longitudinally placed between the fixed rail and the switch-tongue and flexibly secured.

I therefore claim as my invention and desire to secure by Letters Patent—

1. In a foot-guard for a split switch in combination with the fixed rail and the switch-tongue a horizontally-movable bar longitudinally placed between the fixed rail and the switch-tongue and flexibly secured, said bar being adapted to occupy the recess in the side of the fixed rail when the switch-tongue is closed against it, and means for withdrawing the bar from the recess in the fixed rail when the switch-tongue is opened so that the bar will divide the open space between the fixed rail and the switch-tongue, substantially as described.
2. In a foot-guard for a split switch in combination with the fixed rail and the switch-tongue a horizontally-movable bar longitudinally placed between the fixed rail and the switch-tongue, having at one end a flexible connection which allows the bar to move laterally with the switch-tongue, said bar being adapted to occupy the recess in the side of the fixed rail when the switch-tongue is closed against it, and means for withdrawing the bar from the recess in the fixed rail when the switch-tongue is open so that the bar will divide the open space between the fixed rail

and the switch-tongue, substantially as described.

3. In a foot-guard for a split switch in combination with the fixed rail and the switch-tongue, a horizontally-movable bar, longitudinally placed between the fixed rail and the switch-tongue, and flexibly secured at one end by a vertical hinge, which permits the bar to move laterally, said bar being adapted to occupy the recess in the side of the fixed rail when the switch-tongue is closed against it, and means for withdrawing the bar from the recess in the fixed rail when the switch-tongue is opened so that the bar will divide the open space between the fixed rail and the switch-tongue, substantially as described.

4. In a foot-guard for a split switch in combination with a fixed rail and the switch-tongue, a horizontally-movable bar *a a* longitudinally placed between the fixed rail *B*, and the switch-tongue *A*, and secured to the said movable rail or switch-tongue *A* by the hinge *b*, said bar being adapted to occupy the recess in the side of the fixed rail when the switch-tongue is closed against it, and to be drawn from said recess, and the hook *D* attached to the bar *a a* and adapted to engage the switch-tongue, and the shoe *G* attached to the bar *a a* and carrying the hook *H*, substantially for the purpose as hereinbefore set forth.

WILLIAM R. KEENEY.
